UNITED STATES PATENT OFFICE.

ROBERT R. KINTZ, OF MERIDEN, CONNECTICUT, ASSIGNOR TO INTERNATIONAL SILVER COMPANY OF MERIDEN, CONNECTICUT, A CORPORATION OF NEW JERSEY.

DESIGN FOR A SOUP TUREEN OR SIMILAR ARTICLE.

Application filed October 24, 1922. Serial No. 4,076. Term of patent 14 years.

To all whom it may concern:

Be it known that I, ROBERT R. KINTZ, a citizen of the United States, residing at Meriden, in the county of New Haven and State of Connecticut, have invented a new, original, and ornamental Design for a Soup Tureen or Similar Article, of which the following is a specification, reference being had to the accompanying drawing, forming a part thereof.

I claim:

The ornamental design for a soup tureen or similar article as shown.

ROBERT R. KINTZ.
